(57) **CLAIM**

The ornamental design for an open compression-type right angle coaxial cable connector, as shown and described.

DESCRIPTION

FIG. 1 is a front perspective view showing our design for an open compression-type right angle coaxial cable connector; FIG. 2 is a back perspective view thereof; FIG. 3 is a top view thereof; FIG. 4 is a bottom view thereof; FIG. 5 is a left side view thereof, the claimed portion of which is a mirror image to a right side view; FIG. 6 is a front view thereof; and, FIG. 7 is a back view thereof.

The broken line portion of the figure drawings is included to show unclaimed subject matter only and forms no part of the claimed design.
